UNITED STATES PATENT OFFICE

2,037,103

SEMIAUTOMATIC SELF-FEED AND SELF-COILING SNAKE TOOL

Ira D. Yohn, Los Angeles, Calif.

Application October 21, 1931, Serial No. 570,151

21 Claims. (Cl. 15—104.30)

My invention relates to cleaning devices, and more particularly to such devices as are used in cleaning clogged drains of sinks, toilets and the like, although in its broader aspects is not to be limited to such; said device when it is operated will not mar or soil floors, furniture or the fixtures with which said device is to be used, or become filled with extraneous material, such as dirt, rubbish and the like when a drain is treated underneath buildings, obviating the cleaning thereof after use, as is the case with known devices for a similar purpose. It is moreover unnecessary at any time for the hands of the operator to touch the cleaning means or member, such as is necessary in devices heretofore proposed, nor does such means become kinked while in use, all such deleterious effects being effectively overcome.

It accordingly is an object of my invention to provide a novel form of cleaning device in which a cleaning means, such as a snake of any preferred length, and equipped upon one end with a suitable cleaning tool, either of conventional or novel form, is adapted for rotation in forward or reverse direction to provide a forward and retractive movement of said tool, to the end that said snake be fed either semi-automatically, or manually into and out of a drain, said snake being coiled or uncoiled, at any preferred speed, means being provided for this purpose, said device being also equipped with means whereby it may be used either vertically such as when applied to a sink or toilet, or horizontally when used in other relations, such as below a building.

It is also within the province of my invention to provide a novel form of self feeding mechanism consisting of a plural part structure, capable of manual adjustment, to the end that the same may be positioned about the cleaning means, and may optionally be used or not, as in practice preferred or needed.

A still further object of my invention is to provide a manual feeding device for the cleaning means, comprising a plural part structure adapted to be secured to said cleaning means so said means, if desired, may be fed at a faster speed, or adjusted so it may be rendered slidably thereon.

It is also within the province of my invention to equip my novel device with a protective means constructed of suitable material, so that when said device is used, in connection with porcelain sinks or toilets, or highly polished metal, said porcelain or metal will not be marred or damaged in any way.

The above, and further objects and advantages of my invention, as will hereinafter more fully

appear, I attain by the construction described in the specification, and illustrated on the drawing, forming a part of my application.

Reference is had to the accompanying drawing, in which similar reference characters denote similar parts. In the drawing,

Fig. 1 is a perspective view showing one practical application of my invention, illustrating how the invention may be applied to the wash bowl of a bathroom to clean the drain pipe,

Fig. 2 is a somewhat enlarged cross-sectional view, taken on the line 2—2, Fig. 1,

Fig. 3 is a front elevational view of the device, looking in the direction of the arrow 3, Fig. 2,

Fig. 4 is an enlarged fragmentary cross-sectional view, taken on the line 4—4, Fig. 2, looking in the direction of the arrows,

Fig. 5 is an enlarged cross-sectional view, taken on the line 5—5, Fig. 3, looking in the direction of the arrows,

Fig. 6 is an enlarged cross-sectional view taken through the manual feeding device, said device being illustrated in operative position on the cleaning means,

Fig. 7 is an enlarged fragmentary cross-sectional view, illustrating how the cleaning means or snake is anchored to the casing in which it is coiled or uncoiled,

Fig. 8 is an enlarged fragmentary cross-sectional view, taken on the line 8—8, Fig. 2,

Fig. 9 is a similar view, taken on the line 9—9, Fig. 2, and

Fig. 10 is a fragmentary perspective view, illustrating how the invention may be used in a horizontal position.

Describing my invention more in detail, in its broader aspects said invention comprises a novel form of device adapted to be used both horizontally and vertically, or in an angular position. Said device consists of a suitable framework with which is mounted for rotation, a suitable cleaning means or snake, adapted for reciprocation, that is, a forward and reverse movement, either of conventional or novel form. Said cleaning means has positioned on one end thereof a suitable tool which may be inserted in a drain or the like and reciprocated and rotated to clean such drain.

More specifically, my invention comprises a suitable framework 2, which may be of any desired shape, and constructed of any preferred material, which framework 2 may be considered stationary with respect to a movable framework 4, suitably mounted for rotation within said stationary framework 2, any suitable means, such as the crank 6 being provided for rotating said

rotary framework, said crank being secured to said rotary framework in any preferred way, as by the nut 8, both of said frameworks being so constructed that they may be easily assembled and disassembled.

If desired any suitable means, such as the curled portion 10 (Fig. 2, more particularly) may be provided, to be engaged by the finger of the operator to provide different leverage so that the speed of rotation of said rotary framework, and its adjuncts, to be presently described, may be varied. It will, of course, be understood that any other preferred means for accomplishing said rotation may be substituted for that just described.

Any suitable bearings 12 may be provided for the rotation of the framework 4 with respect to the stationary framework 2, and mounted for rotation with the framework 4 is a preferably circular casing 14, constructed of suitable material, and secured to said rotary framework in any preferred way as by a stationary shaft 16 (Figs. 2 and 3), secured to the framework 4 in any suitable way, as by the nut and bearing assembly 18.

The casing 14 is adapted to house the cleaning means or snake 20, provided upon one end with a suitable cleaning tool or device 22, said snake 20 being preferably secured or anchored internally of said casing by any suitable means, such as the clamp 24 (Fig. 7, more particularly), said snake 20 extending through a suitable guide tube 26, preferably extending within the casing 14 (Fig. 2, more particularly), said guide tube 26 being anchored to the shaft 16 by any suitable means, such as the clamp or strap 28 by means of a screw bolt 30 (Fig. 4), said guide tube 26 being anchored to the rotatable framework 4 by the screw collar and annulus assembly 32 (Fig. 9).

The guide tube 26 is preferably bent to extend in an arc around the axis of the casing 14 as shown in Figure 3. This avoids the delivery of the snake 20 from the guide tube on a radius of the casing and thereby prevents kinking of the snake in the casing.

Any suitable mounting 34 for the framework 2 may be provided, which may be of skeleton or other form, and may be secured to the framework 2 in any preferred way, as indicated by the flange and bolt assembly 36 (Fig. 3), any suitable material 38, such as felt, leather, rubber or the like being provided on the outer end of said mounting 34 to prevent marring, scratching or damaging the porcelain or highly polished metal on which the device is to be positioned.

The mounting 34 is also provided with a suitable snake guide 40, secured thereto as desired (Figs. 3 and 8), and through which said snake 20 is guided as it is payed out from the device into the drain.

To provide for a semi-automatic feed of the snake 20, the device 42 (Fig. 5) is provided, which device preferably comprises a pair of relatively movable members 44 having associated therewith in any preferred way as by bolts or screws the clamping devices 46, which are internally threaded to engage the outer threaded portion of the snake 20, a suitable fulcrum 48 being associated with one of the members 44 so that the other may be fulcrumed thereon, a thumb screw assembly 50, associated with both said members 44 being provided to adjust said members toward and away from each other, the adjustable bolt and spring means 52 being provided to oppose the movement of said bars. By adjusting the thumb means 50, the threaded clamps 46 may be caused

to engage the snake 20, so as the framework 4 and casing 14 are rotated, the snake 20 will be fed through the guide tube 26 and through the clamps 46, the tool 22 entering the drain as said snake is uncoiled. By reversing the movement of said framework and casing the snake 20 is coiled and withdrawn from the drain. For observation purposes, the casing 14 may be provided with any preferred number of sight openings 54, which may also be used for washing the snake and casing.

It may sometimes be desired in practice to operate the snake 20 and its tool 22 manually and directly, without the use of the movable framework 4, as, for example, when an obstruction in a clogged pipe is encountered, which it is more or less difficult to dislodge by actuating the crank 6 or the curled portion 10. To this end the manually operable device 56, more particularly shown in Figure 6, may be employed.

The device 56 comprises a pair of adjustable members 58 having cut out and threaded portions matching the external thread of the snake 20, and the threads of which are adapted to be pressed into engagement with such threads of the snake 20 or released from such engagement, suitable plates 57 and screws 60 being provided, whereby the device may be tightly detachably clamped and secured to such snake 20 for longitudinal and rotary movement jointly therewith so that the snake may be moved by means of such device either rotatably or longitudinally or have both longitudinal and rotatory movement imparted thereto simultaneously manually or by means of a tool operating such device.

In operation, the semi-automatic feed device 42, (Figure 5, more particularly) is first rendered inoperative by loosening its parts 46, 50 and 52, which frees the snake from such semi-automatic device and permits the longitudinal movement of the same through the tube or guiding sheath portion 26, without hindrance. When by grasping the manually operable device with the hand and rotating the same, together with the snake 20 releasably secured thereto, the snake 20 may be suitably manipulated as by reciprocation and rotation, to penetrate the obstruction and otherwise suitably clear the drain of the obstruction.

It is also desirable in practice that the framework 2 may be used horizontally as well as vertically. Accordingly, a suitable stand 62, which may be pivoted to the framework 2, may be provided, which stand may be rotated on its pivot out of the plane of said framework, and placed at right angles thereto. This permits the use of the invention horizontally, as, for example, when working below buildings.

In operation when it is desired to feed the snake into a drain or the like this may be done manually by releasing the clamps 46 and the clamps 58 and pulling the snake out by hand whereupon the end 22 may be inserted in the drain. Also the snake may be fed forwardly into the drain by rotating the crank 6 in the proper direction so that the frame 4 and casing 14 is revolved on the axis of the bearings 12 and, the clamps 46 having been applied, the snake is screwed through these clamps and caused to feed forward. Similarly, if the crank be rotated in the opposite direction, with the clamps 46 closed on it, it will screw backwardly through the clamps and be fed into the casing 14. In all cases the casing 14 will be caused, by the action of the snake in withdrawal or storage, to rotate on the shaft 16 dur-

ing such action. Obviously the snake may be reciprocated in the drain when the clamps are applied by simply moving the frame and parts carried thereby toward and from the point of entry of the snake into the drain. If a manual reciprocation of the snake independently of the casing is desired one may release the clamps 46 and grip the clamps 58 by his hand to firmly grasp the snake 20 between them. He may then, while holding the frame and casing stationary, reciprocate the snake in the drain.

In accordance with the provisions of the patent statutes, I have described the principle of operation of my invention together with the apparatus which I now consider to represent the best embodiment thereof; but I desire to have it understood that the apparatus shown is only illustrative, and that the invention can be carried out by other means.

I claim as my invention:

1. The combination with a threaded snake and means to rotate the same; of a relatively immovable feeding means engageable with and disengageable from said snake and comprising relatively movable members, means on one of said members whereby the other member may be fulcrumed thereon, a pair of internally threaded clamps carried by said members, means associated with one end of each of said members for adjusting said members with respect to each other on said first mentioned means, and means associated with the other end of each of said members for opposing the movement of said members.

2. In a device of the kind described, a supporting frame having two ends, a shaft rotatably supported at one end of the frame, a guide journalled at the other end of the frame in alignment with said shaft, a disc-like housing, means to support said housing at diametrically opposite points by said shaft and guide whereby the housing may be revolved on a diameter extending axially of the shaft and guide, and a plumber's snake extending through said guide and into the housing, said housing having an opening in one side and spaced inwardly from its periphery and the guide extending to said opening to lead the snake into the housing.

3. In a device of the kind described, a supporting frame having two ends, a shaft rotatably supported at one end of the frame, a guide journalled at the other end of the frame in alignment with said shaft, a disc-like housing, means to support said housing at diametrically opposite points by said shaft and guide whereby the housing may be revolved on a diameter extending axially of the shaft and guide, and a plumber's snake extending through said guide and into the housing, said housing having an opening in one side and spaced inwardly from its periphery and the guide extending into said opening to lead the snake into the housing.

4. In a device of the kind described, a supporting frame having two ends, a shaft rotatably supported at one end of the frame, a guide journalled at the other end of the frame in alignment with said shaft, a disc-like housing, means to support said housing at diametrically opposite points by said shaft and guide whereby the housing may be revolved on a diameter extending axially of the shaft and guide, and a plumber's snake extending through said guide and into the housing, said housing having an opening in one side and spaced inwardly from its periphery and the guide extending into said opening to lead

the snake into the housing, said guide having the end within the housing positioned to lie at an acute angle to a radial line extending from the center of the housing through the extremity of the guide.

5. In a device of the kind described, a supporting frame having two ends, a shaft rotatably supported at one end of the frame, a guide journalled at the other end of the frame in alignment with said shaft, a disc-like housing, means to support said housing at diametrically opposite points by said shaft and guide whereby the housing may be revolved on a diameter extending axially of the shaft and guide, a plumber's snake extending through said guide and into the housing, said housing having an opening in one side and spaced inwardly from its periphery and the guide extending to said opening to lead the snake into the housing, said snake having a screw threaded exterior, and a nut on said supporting frame adjacent said guide through which said snake is screwed whereby rotation of the housing in the frame causes longitudinal movement of the snake.

6. In a device of the kind described, a supporting frame having two ends, a shaft rotatably supported at one end of the frame, a guide journalled at the other end of the frame in alignment with said shaft, a disc-like housing, means to support said housing at diametrically opposite points by said shaft and guide whereby the housing may be revolved on a diameter extending axially of the shaft and guide, a plumber's snake extending through said guide and into the housing, said housing having an opening in one side and spaced inwardly from its periphery and the guide extending into said opening to lead the snake into the housing, said snake having a screw threaded exterior, and a nut on said supporting frame adjacent said guide through which said snake is screwed whereby rotation of the housing in the frame causes longitudinal movement of the snake.

7. In a device of the kind described, a supporting frame having two ends, a shaft rotatably supported at one end of the frame, a guide journalled at the other end of the frame in alignment with said shaft, a disc-like housing, means to support said housing at diametrically opposite points by said shaft and guide whereby the housing may be revolved on a diameter extending axially of the shaft and guide, a plumber's snake extending through said guide and into the housing, said housing having an opening in one side and spaced inwardly from its periphery and the guide extending into said opening to lead the snake into the housing, said guide having the end within the housing positioned to lie at an acute angle to a radial line extending from the center of the housing through the extremity of the guide, said snake having a screw threaded exterior, and a nut on said supporting frame adjacent said guide through which said snake is screwed whereby rotation of the housing in the frame causes longitudinal movement of the snake.

8. In a device of the kind described, a supporting frame having two ends, a shaft rotatably supported at one end of the frame, a guide journalled at the other end of the frame in alignment with said shaft, a disc-like housing, means to support said housing at diametrically opposite points by said shaft and guide whereby the housing may be revolved on a diameter extending axially of the shaft and guide, a plumber's snake extending through said guide and into the housing, said housing having an opening in one side and

spaced inwardly from its periphery and the guide extending to said opening to lead the snake into the housing, said snake having a threaded exterior, a split nut carried by said supporting frame adjacent said guide to grip the snake and thereby cause longitudinal movement of the snake as the housing is revolved in the frame, said nut being arranged for manual opening to release the snake, and spring means urging said nut to close on the snake.

9. In a device of the kind described, a supporting frame having two ends, a shaft rotatably supported at one end of the frame, a guide journalled at the other end of the frame in alignment with said shaft, a disc-like housing, means to support said housing at diametrically opposite points by said shaft and guide whereby the housing may be revolved on a diameter extending axially of the shaft and guide, a plumber's snake extending through said guide and into the housing, said housing having an opening in one side and spaced inwardly from its periphery and the guide extending into said opening to lead the snake into the housing, said snake having a threaded exterior, a split nut carried by said supporting frame adjacent said guide to grip the snake and thereby cause longitudinal movement of the snake as the housing is revolved in the frame, said nut being arranged for manual opening to release the snake, and spring means urging said nut to close on the snake.

10. In a device of the kind described, a supporting frame having two ends, a shaft rotatably supported at one end of the frame, a guide journalled at the other end of the frame in alignment with said shaft, a disc-like housing, means to support said housing at diametrically opposite points by said shaft and guide whereby the housing may be revolved on a diameter extending axially of the shaft and guide, a plumber's snake extending through said guide and into the housing, said housing having an opening in one side and spaced inwardly from its periphery and the guide extending into said opening to lead the snake into the housing, said guide having the end within the housing positioned to lie at an acute angle to a radial line extending from the center of the housing through the extremity of the guide, said snake having a threaded exterior, a split nut carried by said supporting frame adjacent said guide to grip the snake and thereby cause longitudinal movement of the snake as the housing is revolved in the frame, said nut being arranged for manual opening to release the snake, and spring means urging said nut to close on the snake.

11. In a device of the kind described, an open supporting frame having two ends, a revoluble frame rotatably supported in said supporting frame at opposite ends thereof to revolve on an axis extending across the supporting frame, means whereby the revoluble frame may be rotated on its axis, a stub shaft carried by the revoluble frame and extending substantially at right angles thereto and a disc like circular housing substantially axially rotatably mounted on said shaft, one support for said revoluble frame being tubular to constitute a guide, and a plumber's snake extending through said guide and into the housing, said housing having an opening in one side and spaced inwardly from its periphery and the guide extending to said opening to lead the snake into the housing.

12. In a device of the kind described, an open supporting frame having two ends, a revoluble frame rotatably supported in said supporting

frame at opposite ends thereof to revolve on an axis extending across the supporting frame, means whereby the revoluble frame may be rotated on its axis, a stub shaft carried by the revoluble frame and extending substantially at right angles thereto and a disc like circular housing substantially axially rotatably mounted on said shaft, one support for said revoluble frame being tubular to constitute a guide, and a plumber's snake extending through said guide and into the housing, said housing having an opening in one side and spaced inwardly from its periphery and the guide extending into said opening to lead the snake into the housing.

13. In a device of the kind described, an open supporting frame having two ends, a revoluble frame rotatably supported in said supporting frame at opposite ends thereof to revolve on an axis extending across the supporting frame, means whereby the revoluble frame may be rotated on its axis, a stub shaft carried by the revoluble frame and extending substantially at right angles thereto and a disc like circular housing substantially axially rotatably mounted on said shaft, one support for said revoluble frame being tubular to constitute a guide, and a plumber's snake extending through said guide and into the housing, said housing having an opening in one side and spaced inwardly from its periphery and the guide extending into said opening to lead the snake into the housing, said guide having the end within the housing positioned to lie at an acute angle to a radial line extending from the center of the housing through the extremity of the guide.

14. In a device of the kind described, an open supporting frame having two ends, a revoluble frame rotatably supported in said supporting frame at opposite ends thereof to revolve on an axis extending across the supporting frame, means whereby the revoluble frame may be rotated on its axis, a stub shaft carried by the revoluble frame and extending substantially at right angles thereto and a disc like circular housing substantially axially rotatably mounted on said shaft, one support for said revoluble frame being tubular to constitute a guide, a plumber's snake extending through said guide and into the housing, said housing having an opening in one side and spaced inwardly from its periphery and the guide extending to said opening to lead the snake into the housing, said snake having a screw threaded exterior, and a nut on said supporting frame adjacent said guide through which said snake is screwed whereby rotation of the housing in the frame causes longitudinal movement of the snake.

15. In a device of the kind described, an open supporting frame having two ends, a revoluble frame rotatably supported in said supporting frame at opposite ends thereof to revolve on an axis extending across the supporting frame, means whereby the revoluble frame may be rotated on its axis, a stub shaft carried by the revoluble frame and extending substantially at right angles thereto and a disc like circular housing substantially axially rotatably mounted on said shaft, one support for said revoluble frame being tubular to constitute a guide, a plumber's snake extending through said guide and into the housing, said housing having an opening in one side and spaced inwardly from its periphery and the guide extending to said opening to lead the snake into the housing, said snake having a screw threaded exterior, and a nut on said supporting frame adjacent said guide through which said

- snake is screwed whereby rotation of the housing in the frame causes longitudinal movement of the snake.
16. In a device of the kind described, an open supporting frame having two ends, a revoluble frame rotatably supported in said supporting frame at opposite ends thereof to revolve on an axis extending across the supporting frame, means whereby the revoluble frame may be rotated on its axis, a stub shaft carried by the revoluble frame and extending substantially at right angles thereto and a disc-like circular housing substantially axially rotatably mounted on said shaft, one support for said revoluble frame being tubular to constitute a guide, a plumber's snake extending through said guide and into the housing, said housing having an opening in one side and spaced inwardly from its periphery and the guide extending into said opening to lead the snake into the housing, said guide having the end within the housing positioned to lie at an acute angle to a radial line extending from the center of the housing through the extremity of the guide, said snake having a screw threaded exterior, and a nut on said supporting frame through which said snake is screwed whereby rotation of the housing in the frame causes longitudinal movement of the snake.
17. In a device of the kind described, an open supporting frame having two ends, a revoluble frame rotatably supported in said supporting frame at opposite ends thereof to revolve on an axis extending across the supporting frame, means whereby the revoluble frame may be rotated on its axis, a stub shaft carried by the revoluble frame and extending substantially at right angles thereto, and a disc like circular housing rotatably mounted on said shaft, one support for said revoluble frame being tubular to constitute a guide, a plumber's snake extending through said guide and into the housing, said housing having an opening in one side and spaced inwardly from its periphery and the guide extending to said opening to lead the snake into the housing, said snake having a threaded exterior, a split nut carried by said supporting frame adjacent said guide to grip the snake and thereby cause longitudinal movement of the snake as the housing is revolved in the frame, said nut being arranged for manual opening to release the snake, and spring means urging said nut to close on the snake.
18. In a device of the kind described, an open supporting frame having two ends, a revoluble frame rotatably supported in said supporting frame at opposite ends thereof to revolve on an axis extending across the supporting frame, means whereby the revoluble frame may be rotated on its axis, a stub shaft carried by the revoluble frame and extending substantially at right angles thereto and a disc like circular housing substantially axially rotatably mounted on said shaft, one support for said revoluble frame being tubular to constitute a guide, a plumber's snake extending through said guide and into the housing, said housing having an opening in one side and spaced inwardly from its periphery and the guide extending into said opening to lead the snake into the housing, said snake having a threaded exterior, a split nut carried by said supporting frame adjacent said guide to grip the snake and thereby cause longitudinal movement of the snake as the housing is revolved in the frame, said nut being arranged for manual opening to release the snake, and spring means urging said nut to close on the snake.
19. In a device of the kind described, an open supporting frame having two ends, a revoluble frame rotatably supported in said supporting frame at opposite ends thereof to revolve on an axis extending across the supporting frame, means whereby the revoluble frame may be rotated on its axis, a stub shaft carried by the revoluble frame and extending substantially at right angles thereto and a disc like circular housing substantially axially rotatably mounted on said shaft, one support for said revoluble frame being tubular to constitute a guide, a plumber's snake extending through said guide and into the housing, said housing having an opening in one side and spaced inwardly from its periphery and the guide extending into said opening to lead the snake into the housing, said guide having the end within the housing positioned to lie at an acute angle to a radial line extending from the center of the housing through the extremity of the guide, said snake having a threaded exterior, a split nut carried by said supporting frame adjacent said guide to grip the snake and thereby cause longitudinal movement of the snake as the housing is revolved in the frame, said nut being arranged for manual opening to release the snake, and spring means urging said nut to close on the snake.
20. A snake handling and storing implement comprising, a substantially circular casing having an opening in one face spaced inwardly of the periphery of the casing, an elongated support for said casing extending diametrically across the face opposite said opening, a stub axle carried by said support and having the casing centrally mounted thereon for free revolution, said support having at one end guide means for a plumber's snake, said guide means at one end terminating adjacent said opening and at the other end extending out substantially radially from said circular casing, means at the other end of the support whereby it and the casing may be revolved about the axis of the support to rotate the snake, and a resilient and flexible plumber's snake extending through said guide means to enter the casing and coil against its peripheral portion.
21. A snake handling and storing implement comprising, a substantially circular casing having an opening in one face spaced inwardly of the periphery of the casing, said casing being substantially of lenticular form and having a relatively thick central portion and a relatively thin peripheral portion, an elongated support for said casing extending diametrically across the face opposite said opening, a stub axle carried by said support and having the casing centrally mounted thereon for free revolution, said support having at one end guide means for a plumber's snake, said guide means at one end terminating adjacent said opening and at the other end extending out substantially radially from said circular casing, means at the other end of the support whereby it and the casing may be revolved about the axis of the support to rotate the snake, and a resilient and flexible plumber's snake extending through said guide means to enter the casing and coil against its peripheral portion.

IRA D. YOHN.
